Inventor:
Charles E. Buell.

UNITED STATES PATENT OFFICE.

CHARLES E. BUELL, OF NORTH PLAINFIELD, NEW JERSEY, ASSIGNOR TO
GENERAL FIRE EXTINGUISHER COMPANY, OF NEW YORK, N. Y., A
CORPORATION OF NEW YORK.

FIRE-EXTINGUISHING APPARATUS.

No. 818,999.

Specification of Letters Patent.

Patented April 24, 1906.

Original application filed April 20, 1892, Serial No. 429,825. Divided and this application filed September 4, 1901. Serial No. 74,335.

To all whom it may concern:

Be it known that I, CHARLES E. BUELL, of North Plainfield, Somerset county, State of New Jersey, have invented Improvements in 5 Fire-Extinguishing Apparatus, of which the following is a specification, the same being a division of my application for fire-extinguishers filed April 20, 1892, Serial No. 429,825.

My invention consists, primarily, in the combination, with a system of automatic sprinklers, of a main valve apparatus closing the waterway between the main supply-pipe and the distributing-pipes, thermally-actuated devices normally sealing the distributing-pipes, an alarm apparatus held normally out of effective action by a valvular mechanism that is adapted to be moved by the variation of pressure in the pipes of the system due to the opening of a sprinkler and 20 when so moved to bring said alarm apparatus into effective action, substantially as hereinafter described.

My invention further consists in the combination, with the pipes of a sprinkler system, 25 of a means for admitting water thereto from a main supply, a pressure-controlled apparatus having connection to an alarm apparatus and adapted to admit water to said alarm apparatus when a sprinkler opens and the 30 pressure in the system varies, substantially as hereinafter described.

My invention further consists in the combination, with the pipes of a sprinkler system, of a water-motor having connection to said 35 pipes through a pressure-actuated apparatus that in its normal operation admits water to said motor when the pressure in the system is varied by the opening of a sprinkler and an electric generator in operative relation to 40 said motor, the whole arranged and operating substantially as hereinafter described.

In the accompanying drawing the figure represents a sprinkler system having the main riser P, connecting between the main 45 supply-pipe M and the tank T and comprising a double bend constituting a siphon by means of which the water from the tank T can be held by air-pressure from entering into and filling the riser P until a sprinkler 50 melts open and allows the air-pressure to es-

cape, when the water from the tank T will fill riser P and the branch sprinkler-pipe P' and discharge at the opened sprinkler. A pump is shown for supplying gaseous pressure to the system and an escape-valve E for regulating the air-pressure. There is shown a pressure-actuated alarm apparatus comprising gage G, having connection to the riser P and by its index-hand to operate an electric circuit in which is included the electric bell 60 G' and battery B when the pressure in riser P falls below a predetermined point. There is also shown a water-motor W M attached to the alternating-current electric generator D and provided with a bell b and hammer h for 65 sounding a local alarm when the motor is in motion and for generating currents for charging the circuit composed of wires W W' to sound a distant alarm when the motor is given motion by the entrance of water there- 70 to through the pipe P², which has connection to the system through the pressure-actuated valve V and the attached combined piston and valve V' in the cylinder A.

A check-valve C V is shown located in the 75 branch of the main supply which leads to the steam-pump (not shown) to prevent the escape of the air-pressure in the system.

The operation of the apparatus is as follows: When a sprinkler S opens, the water 80 in tank T flows to fill riser P and through pipe P³ to beneath the combined piston and valve V', which by its large area for pressure raises valve V, admitting water from main M to supply the system and also admitting 85 water to pipe P² for giving motion to motor W M. A valve R is shown at the inlet of the large pipe of the siphon in tank T to prevent overflow of the tank when the water from main M is admitted to the system. There 90 are also shown the feed-pipe and overflow-pipe for regulating the flow of water to and out of the tank T. A drip C is shown at the lowest point of the system for dripping the same. 95

I do not claim herein the combination, with the supply-pipe leading from a local supply to the distributing-pipes, of an auxiliary supply-valve arranged to be operated by pressure of water from the pipes leading from the 100

local supply to the distributing-pipes, as this is disclosed and claimed in my main application above referred to.

What I claim is—

- 5 1. The combination with a system of automatic sprinklers, of a main-valve mechanism, means for automatically operating the said valve mechanism by variations of pressure in the pipes of the system, a motor having connection to said system through the valve mechanism, an electric generator connected to the said motor and circuit connections joined to said generator.
- 15 2. The combination with a sprinkler system of a mechanism for giving fire-alarms when a sprinkler opens by heat that comprises a motor operated by water admitted thereto automatically by a lowering of pressure in the pipes of the system, a generator of 20 electricity driven by said motor, and having connections to an alarm apparatus, and an alarm apparatus having connection to the pipes of the system through a pressure-indicating device that is independent of the said 25 motor.
3. The combination with an incased valve normally excluding water from the pipes of a sprinkler system, of a tank located above said valve and having a siphon connection 30 thereto and to the system of sprinklers, means for maintaining air-pressure normally in the system that is adapted to prevent water from the tank acting to raise said valve until the pressure in the system is destroyed 35 by the opening of a sprinkler, a water-motor provided with connections to an alarm apparatus, and pipe connections from said water-motor to the interior of the casing of said valve.
- 40 4. In a fire-extinguishing system the combination with a valve mechanism for normally excluding the water from the system, of a main supply-pipe, a main riser-pipe, and a valve closing the waterway between the 45 said pipes, connections from the main riser to a supply of gaseous pressure, and a connec-

tion from the said valve mechanism to a combined water-motor and electric generator, the whole arranged and operating substantially as described.

50

5. An alarm for automatic sprinklers comprising a dry-pipe-valve mechanism with pipe connections from the said mechanism at a point from which the water is normally excluded to a water-motor, an electric generator adapted to be operated by said motor, wire connections to a remote point, and a local alarm that is adapted to be made operative by the said motor.

55

6. The combination with a system of 60 sprinklers, of a tank located above the sprinklers, means for maintaining gaseous pressure to normally hold the water from entering from the said tank into the said pipes, an auxiliary supply of water that is normally 65 turned off and a valve for controlling the same that is adapted to be operated by the pressure from the tank to turn on the auxiliary water-supply when a sprinkler opens, a water-motor having connection to the system and adapted to receive water therefrom when the water from the tank operates the valve controlling the auxiliary supply, and an electric generator in operative relation to said motor for transmitting alarm-signals to 70 denote the movement of said valve.

75

7. In a pressure-utilizing system the combination of a dry-pipe valve for normally closing the waterway between the main supply and the pipes of the system, thermally-actuated devices sealing the distributing-pipes of the system, a pressure-controlled alarm apparatus connected to the system and mechanism for operating the main valve and normally excluding water from said 85 alarm apparatus and adapted to admit water to said apparatus when a sprinkler opens.
